(57) **CLAIM**

The ornamental design for a honing tool, as shown and described.

DESCRIPTION

FIG. 1 is a top, rear, and left-side perspective view of a first embodiment of the honing tool;

FIG. 2 is a right-side elevation view thereof;

FIG. 3 is a left-side elevation view thereof;

FIG. 4 is a bottom plan view;

FIG. 5 is a top plan view;

FIG. 6 is a rear elevation view; and

FIG. 7 is a front elevation view thereof.

FIG. 8 is a top, rear, and left-side perspective view of a second embodiment of the honing tool;

FIG. 9 is a right-side elevation view thereof;

FIG. 10 is a left-side elevation view thereof;

FIG. 11 is a bottom plan view thereof;

FIG. 12 is a top plan view thereof;

FIG. 13 is a rear elevation view thereof; and,

FIG. 14 is a front elevation view thereof.

The second embodiment of the honing tool shown FIGS. 8-14 differs from the first embodiment shown in FIGS. 1-7 only in that the middle part of the honing tool is made of a different material than the rest of the tool, whereas in the first embodiment the tool is made of one material. All other surfaces are the same in both embodiments.

The broken lines shown in the drawings illustrate portions of the honing tool that forms no part of the claimed design.

1 Claim, 12 Drawing Sheets
